PAGE 2

Fig. 2.

Fig. 3.

Fig. 4.

Fig. 5.

FIG. 1 is a top plan view of a lavatory showing my new design.

FIG. 2 is a front elevational view thereof.

FIG. 3 is a rear elevational view thereof.

FIG. 4 is a side elevational view thereof.

FIG. 5 is a cross-sectional view taken on line 5-5 of FIG. 2.

The characteristic feature of my design resides in the striations extending from the drain outlet area of the lavatory towards the front of the bowl where they divide into separate substantially similar swirls on opposite sides of the lavatory bowl and each swirl curves back along the opposite sides of the bowl.

I claim:

The ornamental design for a lavatory or similar article, as shown and described.
